UNITED STATES PATENT OFFICE.

CHARLES H. LANDENBERGER, OF PHILADELPHIA, ASSIGNOR TO HIMSELF,
MARTIN LANDENBERGER, AND MARTIN LANDENBERGER, JR., OF SAME
PLACE, AND CHARLES WEILER, OF LANDENBERG, PENNSYLVANIA.

DESIGN FOR SHAWL.

Specification forming part of Design No. 7,531, dated July 7, 1874; application filed June 27, 1874.
[Term of Patent 3½ years.]

CASE A.

To all whom it may concern:

Be it known that I, CHARLES H. LANDENBERGER, of Philadelphia, Pennsylvania, have produced or invented a Design for a Shawl Fabric, of which the following is a specification:

The nature of my design for a shawl fabric is clearly illustrated by the diagram, Figure 1 of the accompanying drawing, in which it will be observed that the pattern is composed of a series of short parallel bars, *a*, inclined or beveled at their opposite ends, and arranged in sets *b c d*, &c., those of one set being alternated with, and extending between, the bars of the adjoining set, as shown.

When but two colors are used in regular succession, as shown in Fig. 1, the pattern will be well defined, but by using threads of more

than two shades or colors, as shown in Fig. 2, the bars *a* may be merged or blended into each other, so as to present various pleasing effects, without, however, changing the character of the design.

Irrespective of the colors employed, I claim—

The design for a shawl-pattern, composed of short parallel bars *a* inclined or beveled at their opposite ends, and arranged as described, and as represented in and by the accompanying drawing.

In testimony whereof I have signed my name to this specification in the presence of two subscribing witnesses.

CHARLES H. LANDENBERGER.

Witnesses:

WM. A. STEEL.

HARRY SMITH.
